UNITED STATES PATENT OFFICE

LOUIS L. DRIGGS, JR., OF NEW ROCHELLE, NEW YORK

CANNON

Application filed February 11, 1931. Serial No. 515,102.

The present invention relates to cannon, and more particularly to a light and simply constructed gun of the breech loading type adapted for use with fixed ammunition.

It is an object of the present invention to provide a construction which may be used in a breech loading cannon of any type, but which is particularly advantageous in low pressure guns. For instance, the construction would be particularly suitable for trench guns or mortars handling the regular types of ammunition at low muzzle velocity. In trench guns, reduction of weight is of prime importance. The pressure employed in such guns is low, so that a thin breech block may be used, but such a thin breech block would not permit the machining of a long enough slot in its edge for receiving a crank arm operating in this position. The rear face of the breech block, however, provides ample dimensions to accommodate an operating arm which swings in a plane parallel to the rear face of the block.

It is an object of the present invention to provide a strong durable gun capable of handling relatively large ammunition and which at the same time is relatively light in construction so that it may be quickly and easily handled, and to provide a gun using low pressure and wherein the breech block may be made relatively thin.

Another object of the invention is to provide a novel means for operating the breech block and for mounting the same to slide transversely of the axis of the bore of the gun and which may be quickly and easily closed into relatively tight position, and which may be quickly and easily opened for reloading.

Another object of the present invention is to provide an improved construction of gun wherein the rear side of the breech block may be utilized for accommodating the operating lever and wherein the hammer may have a clear passage-way at the rear of the block for contact with the firing pin.

A further object of the present invention is to provide a construction of this character which not only reduces the relative weight of the gun without sacrificing strength and

necessary sizes of the various parts, but which may be incorporated in a gun having the usual recoil mechanism and which may be mounted for the various necessary adjustments.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a side elevation of a cannon constructed according to the present invention, the gun barrel and adjacent parts being shown in section.

Figure 2 is a rear elevation of the cannon in the closed position of Figure 1, the mounting being removed.

Figure 3 is a detail rear elevation of the breech block.

Figure 4 is a rear elevation of the cannon with the breech block in open position and showing the parts in an adjustment opposite to that shown in Figure 2, and

Figure 5 is a horizontal section taken through the rear end portion of the cannon or gun substantially on the line 5-5 of Figure 4.

Referring now to the drawings, 10 designates the barrel of a gun which is provided with a smooth interior surface and which has at its rear end the usual ammunition chamber 11 adapted to receive the ammunition shell 12 in which is fitted the tail piece 13 of a projectile 14, the latter extending forwardly in the barrel 10.

Suitably fitted to the rear end of the barrel 10 is a frame 15 which carries a sliding breech block 16. The frame 15 is provided in its upper and lower sides with oblique guides or ribs 17 which interfit with correspondingly shaped grooves or channels 18 formed in the upper and lower edge portions of the breech block 16. The breech block 16 also carries a centrally and axially disposed firing pin 19 of usual construction adapted to engage the base 20 of the shell 12 when fitted in the chamber 11 of the bar-

rel. The ribs or guides 17 and the grooves 18 are so inclined transversely with respect to the axis of the gun as to advance the breech block 16 against the rear end of the 5 chamber 11 when the breech block is moved inwardly into the position shown in Figures 1 and 2 and which when the breech block 16 is slid laterally out of register with the chamber 11, as shown in Figures 4 and 5, as 10 to clear the rear end of the chamber 11 and admit of the withdrawal of the shell 12 for reloading.

The breech block 16 is provided at one edge with a semi-circular recess or cut-away 15 portion 21 which is of suitable radius or size as to free the breech 20 of the shell when the block 16 is withdrawn and which at the same time will provide ample extensions at the upper and lower edges of the block 16 to 20 maintain a proper purchase of the breech block on the guides or ribs 17 when the breech block is in open position.

For operating the breech block, the frame 15 is provided at one side, toward which the 25 breech block slides, with a bracket arm 22 within which is rotatably mounted a shaft 23, the latter having its axis substantially parallel to that of the gun and which carries at its forward end an arm 24 with a crank 30 pin 25 on its outer end which extends forwardly and moves in a slot 26 provided in the rear face of the breech block 16 and adjacent the end thereof.

As shown particularly in Figure 3, the slot 35 26 is vertically disposed throughout the major portion of its length and the lower end of the slot 26 is slightly curved outwardly so as to conform to the arc on which the pin 25 travels after the breech block 16 has been 40 moved into a fully closed position.

The frame 15 is provided at its side adjacent the bracket 22 with a vertically disposed web portion 27 which has at its forward side a recess 28 to accommodate the 45 outer end portion of the arm 24 when the latter is overturned inwardly to advance the breech block 16 into a closed position.

A crank arm 29 is fixed upon the rear end of the shaft 23 and at its inner end carries 50 a stop lug 30 adapted to engage beneath a correspondingly disposed stop lug 31 mounted on the bracket 22 for limiting the outward and downward swinging movement of the crank arm 29 when moved into an open position, such as shown in Figures 4 and 5.

The outer end of the crank arm 29 carries a handle 32 which, as best shown in Figure 3, is slidably mounted on a tube 33 and normally held in a forward position by 60 means of a spring 34 acting through a pin 35. The forward end of the pin 35 has a point or projection 36 adapted to enter into a socket opening 37 formed in the rear side and upper intermediate portion of the frame 65 15 for locking the crank arm 29 in a raised

closed position. The crank arm 29 is provided on its outer end with a lip 37 adapted to move into position behind a spaced lug 38 also disposed on the frame 15 when the arm 29 is in closed position. The lip 37 and the lug 38 hold the arm 29 firmly against the rear side of the frame 15 so that vibration of the gun will not accidentally shift or move the arm 29.

The firing pin 19 is exposed at its rear end through the rear side of the breech block 16 and a hammer 39 is mounted upon a bell crank lever 40 which is pivoted at 41 to the rear side and lower portion of the frame 15 in position to bring the hammer 39 into alignment with the firing pin 19 when the bell crank lever 40 is swung upwardly.

The barrel 10 may be mounted in any suitable manner but is preferably slidably mounted in a sleeve 42 having trunnions 43 rotatably supported in a swivel frame 44. The frame 44 rises above the sleeve 42 and carries a recoil cylinder 45 with its parts and rearwardly from which projects a rod 46 which is secured to a lug 47 extending upwardly from the frame 15.

In operation, when it is desired to load the gun the handle 32 is grasped and drawn backwardly to release the point or pin 36 from the socket 37. The crank arm 29 is now swung outwardly and downwardly to turn the shaft 23 and swing the arm 24 upwardly and outwardly with respect to the frame 15. This action raises the pin 25 in the slot 26 with the result that the breech block 16 is first released from interlocking engagement with the pin 25 through the arm 24, as shown in Figure 2, and subsequently the pin 25 engages the outer side of the slot 26 and draws the breech block 16 outwardly or laterally of the gun. This movement of the breech block slides the same upon the guides or ribs 17 with the result that the breech block is retracted from the chamber 11 of the barrel and is carried to one side thereof until the recess 21 of the breech block clears the rear end of the barrel chamber and permits the introduction of the ammunition into the chamber 11 from the rear end there-

of.

100 To close the breech, the opposite operation takes place wherein the crank arm 29 is swung back into closed position as shown in Figure 2, this movement carrying the arm 24 inwardly and downwardly so as to move the pin 25 in the slot 26 and force the breech block 16 not only inwardly but also against the rear end of the barrel chamber 11. This 110 brings the firing pin 19 into proper relation with respect to the ammunition shell 12 and also in line with the path of the hammer 39. The stops 30 and 31 restrict the outward swinging movement of the crank arm 29 and the outward sliding movement of the breech block 16.

It is of course understood that cannon or guns of this type are provided with extractors as a necessary part of modern practical structures, but as these extractors form no part of the present invention, the same have been omitted in the illustration.

It is obvious that various changes and modifications may be made in the details of construction and design of the above specifically described embodiment of this invention without departing from the spirit thereof, such changes and modifications being restricted only by the scope of the following claims.

What is claimed is:—

1. In a cannon, a barrel, a frame mounted across the rear end of the barrel and having guide ribs therein, a breech block slidably mounted upon said ribs in the frame and disposed to engage against the rear end of the barrel when the breech block is slid inwardly, and manual means connected to the breech block and mounted on the frame for sliding the breech block into and out of position, a portion of said manual means adapted to be telescopically received and concealed by said frame when the breech block is in its innermost position.

2. In a cannon, a barrel, a frame mounted across the rear end of the barrel, a breech block slidably mounted in the frame, said frame and breech block having interfitting ribs and grooves extending transversely relatively to the axis of the gun, an arm pivotally mounted upon the frame and having a pin on its outer end, and means for swinging the arm, said breech block having a slot in its face for the reception of said pin and with the slot arranged at an angle to the path of travel of the breech block for sliding the same into and out of position upon the swinging of the arm.

3. In a cannon, a barrel, a frame mounted across the rear end of the barrel, a breech block slidably mounted in the frame, said frame and breech block having interfitting ribs and grooves disposed obliquely with respect to the axis of the barrel for advancing the breech block toward the rear end of the barrel when the breech block is slid inwardly, a shaft pivotally mounted in the frame at one side thereof, a handle on the rear end of the shaft for turning the same, an arm on the forward end of the shaft, and a pin on the outer end of said arm, said breech block having a vertical groove in its rear face adjacent said arm for the reception of said pin for shifting the breech upon the turning of said shaft.

4. In a cannon, a barrel, a frame mounted across the rear end of the barrel and having obliquely disposed ribs in its upper and lower walls, a breech block slidably mounted in the frame and having oblique grooves in its upper and lower edges for the reception

of said ribs to guide the breech block in its transverse movement, and a crank arm structure mounted on one side of the frame rearwardly of the breech block and connected to the latter for shifting the breech block 70 upon the turning of said crank arm structure.

5. In a cannon, a barrel, a frame on the rear end of the barrel provided with a transverse way and having obliquely disposed ribs 75 in its upper and lower faces, a breech block slidably mounted in the way of the frame and having grooves in its upper and lower edges for interfitting engagement with said ribs, said ribs and grooves approaching the rear 80 end of the barrel at their inner ends for guiding the breech block toward the rear end of the barrel when the breech block is moved inwardly, and a crank arm structure carried upon the outer rear portion of said frame and 85 connected to the breech block for moving the latter.

6. In a cannon, a barrel, a transverse frame mounted upon the rear end of the barrel and having oblique ribs in its upper and lower 90 faces, a breech block slidably mounted upon said ribs for movement into and out of the frame, said ribs arranged to guide the breech block into position toward the rear end of the barrel when the breech block is moved inwardly, an arm pivotally mounted upon the side of the frame rearwardly of the breech block and having a pin in its outer end, said breech block having a substantially vertical groove in its rear face for the reception of 95 said pin to shift the breech block upon the swinging of said arm, a crank arm connected to said first arm, a handle on the outer end of said crank arm, and a locking pin carried upon said handle for movement thereby, said frame having a socket in its rear face adapted to receive said pin of the handle when the latter is swung into closed position for locking the breech block in closed position. 100

7. In a cannon, a barrel, a transverse frame at the rear end of the barrel, a breech block slidably mounted on the frame for transverse movement into and out of register with the rear end of the barrel, a firing pin mounted in the breech block and exposed through the rear face thereof, said breech block having near its outer end and in its rear face a substantially vertically disposed slot, a shaft rotatably mounted in the outer side of the frame, an arm on said shaft, a pin on the outer end of said arm engaging in said groove of the breech block, a crank arm mounted on the opposite end of said shaft, and a handle movably mounted upon the outer end of said crank arm for swinging the latter, said frame having a socket in its rear face for interlocking engagement with said handle when moved into closed position. 115

8. In combination, a supporting, guiding frame, a transversely-movable solid breech 120

- block, carrying a firing pin slidable in said frame; said breech block having a vertically-disposed cam slot in the rear face thereof, a bell crank mounted on said frame comprising an operating lever and a cam lever, the latter having a cam member inserted in said slot of the breech block, said parts being so arranged that when the breech block is in open position the cam lever and cam slots are exposed and when in closed position they are received by and enclosed by said frame.
9. In combination, a supporting and guiding frame having horizontally-disposed guide ways therein, a transversely-movable, relatively narrow, solid breech block having a firing pin therein, said breech block having a vertically-disposed, actuating and locking cam slot, the lower end of which diverges laterally, a bell crank mounted on said frame comprising an operating lever and a cam lever engaging in said slot, said parts being so arranged that when the breech block is in closed position its cam slot and cam lever are concealed and enclosed by said frame.
10. In combination, a supporting and guiding frame having horizontally-disposed guide ways therein, a transversely-movable, relatively narrow, solid breech block having a firing pin therein, said breech block having a vertically-disposed, actuating and locking cam slot, the lower end of which diverges laterally, a bell crank mounted on said frame comprising an operating lever and a cam lever engaging in said slot, said parts being so arranged that when the breech block is in closed position its cam slot and cam lever are concealed and enclosed by said frame, a stop on said frame for limiting the movement of the operating lever.
11. In combination, a supporting and guiding frame having horizontally-disposed guide ways therein, a transversely-movable, relatively narrow, solid breech block having a firing pin therein, said breech block having a vertically-disposed, actuating and locking cam slot, the lower end of which diverges laterally, a bell crank mounted on said frame comprising an operating lever and a cam lever engaging in said slot, said parts being so arranged that when the breech block is in closed position its cam slot and cam lever are concealed and enclosed by said frame, a stop on said frame for limiting the movement of the operating lever, and means to lock said operating lever in engagement with said stop.

LOUIS L. DRIGGS, JR.
